US0D1006716S

(12) **United States Design Patent** (10) Patent No.: **US D1,006,716 S**
(45) Date of Patent: ** Dec. 5, 2023

(54) **CHILD TRAY FOR A VEHICLE**

(71) Applicant: **Essentially Engineered, LLC**, Arvada, CO (US)

(72) Inventor: **Jacob Lovasz**, Arvada, CO (US)

(73) Assignee: **Essentially Engineered, LLC**, Cheyenne, WY (US)

(**) Term: **15 Years**

(21) Appl. No.: **29/834,596**

(22) Filed: **Apr. 13, 2022**

(51) LOC (14) Cl. **12-16**

(52) U.S. Cl.

USPC **D12/425**

(58) **Field of Classification Search**

USPC D12/423, 424, 421, 192, 400, 425

CPC B65D 85/68; B60R 7/00
